CLAIM

The ornamental design for an in line extension cord tap, as shown and described.

DESCRIPTION

FIG. 1 presents a top pictorial view of an in line tap embodying my ornamental design.

FIG. 2 presents a top plan of the in line tap shown in FIG. 1.

FIG. 3 presents a left side elevational view of the in line tap shown in FIG. 1.

FIG. 4 presents a bottom view of the in line tap shown in FIG. 1.

FIG. 5 presents a rear elevational view of the in line tap shown in FIG. 1; and,

FIG. 6 presents a front elevational view of the in line tap shown in FIG. 1.

The right side elevational view is a reverse of FIG. 3.

The broken lines in the drawings are for illustrative purposes only and form no part of the claimed design.
